UNITED STATES PATENT OFFICE.

GOTTLIEB KLENK, OF DEFIANCE, OHIO, ASSIGNOR, BY MESNE ASSIGNMENTS, TO THE DEFIANCE PRESSED STEEL COMPANY, A CORPORATION OF OHIO.

METAL BOX.

1,139,534.

Specification of Letters Patent.

Patented May 18, 1915.

Application filed July 13, 1907. Serial No. 383,642.

To all whom it may concern:

Be it known that I, GOTTLIEB KLENK, a citizen of the United States, residing at Defiance, in the county of Defiance and State 5 of Ohio, have invented certain new and useful Improvements in Metal Boxes, of which the following is a specification.

This invention relates to improvements in sheet metal boxes and more especially to improvements in skids for the bottoms of boxes of this type, the same being constructed in such manner as to offer substantial reinforcement.

The invention also relates to the specific 15 details of construction and arrangement of parts, which will be hereinafter described and particularly pointed out in the claims.

In the drawings—Figure 1 is a perspective view of my improved box looking from 20 the underside. Fig. 2 is a detail bottom plan view of one corner of the box. Fig. 3 is an enlarged fragmentary cross sectional view taken on a transverse line through the bottom of the box. Fig. 4 is a detail perspective view of one corner of the bottom of 25 a box. Fig. 5 is a detail view of one of the bottom reinforcing strips in blank form. Fig. 6 is a detail perspective view of a portion of the bottom section and a skid. Fig. 30 7 is a detail perspective view of a portion of said bottom. Fig. 8 is a perspective view of a portion of a solid bottom section, and a skid. Fig. 9 is a similar view of said bottom to illustrate particularly the tongues. Fig. 10 is a detail transverse section on the 35 line 10—10, Fig. 11. Fig. 11 is a detail perspective view of a portion of the bottom shown in Figs. 1 and 2, but showing a slightly different form of applying the 40 tongues. Fig. 12 is a detail section on the line 12—12, Fig. 11. Fig. 13 is a detail section on the line 13—13, of Fig. 8.

The numeral 1, indicates side sections, and 45 2, end sections of my improved box. The end and side sections are folded upon each other to provide substantial corner seams 3. The top edges of said sections are also beaded to inclose a reinforcing element 4.

The numeral 5, indicates a bottom section, 50 provided with a series of openings 6, for the passage of dirt, etc., whereby the box can be readily cleaned and kept perfectly sanitary, and for further preventing of the utilization of the box for other than the purpose for which it was designed. The bot-

tom section is preferably formed from a single sheet of metal, having its edges crimped with the side and end sections, to hold the box securely together. Fitting against the underside of the bottom section 60 adjacent all four sides, are reinforcing strips 7, having their edges also crimped with the sides, ends and bottom to provide a supporting flange 8, as shown in Fig. 3. The inner end of each strip 7, is formed into a bead, 65 and passing through said beads is a reinforcing element 9, thereby providing a flange 10. This flange extends across the bottom of the box near each of its lower edges and is spaced from the outer marginal 70 edges of the box, to afford means for convenient stacking.

The flange 10, which is of a rectangular configuration, provides an elongated bearing or floor engaging surface. The rest between 75 this flange and the extreme outer marginal edges of the bottom of the box is adapted to engage the upper edges of a box below, when several boxes are stacked one upon the other, and the flanges 10 not only act as floor engaging surfaces under ordinary circumstances, but also serve to prevent lateral displacement of the boxes when they are 80 stacked.

The detail construction of the formation 85 of the flanges 8 and 10, at the bottom of the box forms no specific part of this invention, the same being shown and described in my Patent No. 813,976, February 27, 1906, re-issued April 7, 1908, as No. 12,775. I do, 90 however, believe that this feature, in combination with skids and the particular form of reinforcing strips which I will now proceed to describe, is new in the art.

The strips 7, extending lengthwise of the 95 bottom of the box adjacent the side edges, have extensions 11, as shown in Figs. 2 and 5, while the strips extending along the ends of the bottom are cut off straight at their ends. The extensions 11, project from the 100 end of the flange 10, to the outer edge of the box, to rigidly and substantially brace the corners to resist the downward strain, and at the same time assist in tightly tying the flanges 8 and 10, together.

The skids 12, each consist of side wings 105 13—13, and a centrally disposed downwardly extended bulged portion 14, the bottom of which is on a plane with the bottom of the flange 10. The skids may be applied 110

to bottoms provided with the openings 6, or they may be used in connection with a solid bottom. The skids may be secured in any of several ways. As shown in Figs. 5 1, 2, 6 and 7, adjacent the openings 6, are tongues 15, stamped from the bottom section and bent over on themselves to engage the wings 13. When the bottom is solid, however, I prefer to stamp the tongues 15' 10 from the metal, as shown in Figs. 8 and 9, and confine the wings 13 between them and the bottom. When using this construction, the tongues 15' are crimped, with considerable pressure, which forces the wings 13 in 15 the openings 16 as indicated in Figs. 8 and 13. The wings are thus recessed at intervals, as at 16—16', to receive the tongues 15'. The depth of this recess is such that the recessed portions of the wing are held in a 20 position of exact alinement with the sheet metal of the box bottom. In other words, the recessed parts of the wings 13 lie in the same horizontal plane with the sheet metal of the bottom, the plane of the upper face 25 of the recessed portions being coincident with the plane of the upper face of the sheet metal of the bottom so that a smooth uninterrupted surface is provided on the inner side of the box bottom which will not 30 catch particles of rubbish, or furnish a lodgment for dirt. This arrangement provides a bite and prevents lateral displacement of the skids, and less liability of loose joints. When using the form of tongues shown in 35 Figs. 6 and 8, it is evident that the interior of the bottom will be smooth, which under certain circumstances is preferable.

If desired the tongues may be made from 40 separate pieces, as indicated in Figs. 10, 11 and 12. The tongues are here indicated at 14', and consist of strips of metal bent around the necks formed between openings 6, the ends 15'' fitting in openings 6, and engaging the under sides of the wings 13. 45 Obviously this construction performs the same result as that heretofore noted. The skids when secured in place by the tongues, are of such length that their ends abut against the flanges 10, which construction, 50 coupled with the clamping action of the tongues, prevents the skids becoming laterally displaced, and at the same time serves to add strength to the bottom of the box.

The peculiar arrangement of the flange 55 10, forms an important combination with the skids, in that the endwise thrust of the latter, is resisted, which greatly tends to prevent the joints becoming loose when in use. For were it not for this strong and 60 substantial flange the wings would in a short time work from under the tongues.

The invention as described is extremely simple, and is effective to accomplish the desired result. The skids must be secured 65 rigidly to the box, to withstand the rough

handling, and to this end, I have combined the tongues with the flanges in such manner as to make the combination effective.

Boxes provided with stacking flanges and a central skid in the manner above described 70 are capable of being piled one upon the other without the possibility of lateral displacement of any one of the pile and, at the same time, each of the boxes can be used upon a conveyer consisting of a succession 75 of rollers. When thus used, the skid serves to prevent the end flanges 10 from dropping between rollers if the rollers are shorter than the distance between the side flanges 10; and the fact that these skids 80 extend up to and abut against the end flanges 10 not only insures a correct engagement of the box with the conveyer rollers, but also strengthens the end flanges by 85 acting as a strut between them. Furthermore, the skid, having its lower face flush with the lower face of the flanges 10, furnishes additional floor engaging area which will prevent the boxes from moving too freely upon a flat surface. The presence 90 of the depending stacking flange 10 makes it desirable to equip the box with this additional friction bearing surface.

I do not claim as a part of my present invention the construction at each corner of 95 the bottom of the box which consists of the extension 11 on one of the strips 7 crimped into the adjacent part of the supporting flange 8. This feature is covered by my co-pending applications for sheet metal boxes, 100 Serial No. 743,971, filed January 24, 1913, as a division of this application.

What I claim is:—

1. A box having a bottom, a skid on the bottom having horizontally projecting 105 edges, tongues secured to the bottom and overlapping the edges of the skid, and a flange depending from the box a short distance from the edges of the latter and adapted to prevent lateral displacement when several boxes are stacked, the ends of the skid abutting against the flange and the bottom planes of the skid and flange being coincident.

2. A metal box including flanges extending across the box bottom parallel to and spaced from the end edges of the latter, and a skid structurally separate from the box bottom but secured thereto with its ends abutting the respective flanges, said flanges 115 and skid being of equal projected depth beyond the bottom of the box.

3. A metal box having a bottom formed with projecting tongues, and a skid adapted to be held between the tongues and box 125 bottom, said tongues being crimped into the material of the skid to offset those portions of the skid engaged by the tongue, whereby said tongues interlock with the skid and the engaging portions of the skid lie in the 130

same horizontal plane with the sheet metal of the bottom.

4. A metal box having a bottom formed with projecting tongues, and a skid having 5 wings to be engaged between the tongues and box bottom, the tongues being crimped into the wings to form tongue-receiving recesses in said wings and to cause the tongue engaging parts of the skids to lie in the same 10 horizontal plane with the sheet metal of the bottom.

5. A metal box bottom formed with tongues struck from the material of the bottom, and a skid having laterally-projecting 15 wings to be engaged between the tongues and box-bottom, the tongues being crimped into the wings to form tongue-receiving recesses therein and to cause the tongue engaging parts of the skids to lie in the same 20 horizontal plane with the sheet metal of the bottom.

6. The combination in a metal box, with a sheet metal bottom formed with depressed tongues struck from it, of a U-shaped skid 25 provided with wings 13 abutting against the lower face of the bottom and bent at intervals to rest on top of said tongues and in the plane of the sheet metal of the bottom.

7. In a rectangular sheet metal box, the 30 combination of a supporting flange at the lower edges of the side and end walls, a stacking flange projecting downward from the bottom of the box and parallel to and inset inward from the four outer edges 35 thereof, and a supplemental flange flush with the said stacking flange, the said supplemental flange extending from one to the other of two parallel parts of the stacking flange and being positioned between the 40 other two parallel parts.

8. In a metal box, a sheet metal bottom, a depending bottom flange, rectangular in configuration and spaced inwardly from the bottom edges so as to provide a stacking 45 rest outside of the flange, a separate U-shaped skid lying generally in the plane of said bottom flange and extending from one side of said flange to the side opposite, being flush with said bottom flange and adapting 50 ed to provide a box supporting runner supplementary to the said bottom flange, to prevent inward bending of the abutting parts of said bottom flange and being secured to the sheet metal of the bottom so as to act as 55 a strengthening rib therefor.

9. In a rectangular metal box, the combination of a sheet metal bottom, a depending stacking flange on the box bottom and around its four edges, and a U-shaped runner or skid having vertical side walls and a 60 relatively broad horizontal bottom wall

flush with the bottom plane of the box supporting flange, this skid or runner being made from sheet metal separate from the bottom but rigidly secured thereto in such 65 position that it extends from one side of the said box supporting flange against which it abuts, up to and against the opposite side of the said box supporting flange.

10. In a sheet metal box the combination 70 of side and end walls suitably secured together, a bottom secured to the side and end walls, a box supporting flange projecting downward from the bottom along lines near the four edges thereof, and a skid structurally separated from the bottom but secured thereto with its ends abutting against opposite parts of the said flange, the bottom extremities of the flange and of the skid 75 lying in the same horizontal plane. 80

11. In a sheet metal box the combination of side and end walls suitably secured together, a bottom secured to the side and end walls, a box supporting flange projecting downward from the bottom along lines near 85 the four edges thereof, a skid beneath the bottom with its ends abutting against the opposite parts of the said flange, and sheet metal tongues connected with the bottom and engaging the skid for securing the skid 90 to the bottom.

12. In a sheet metal box the combination of side and end walls suitably secured together, a bottom secured to the side and end walls, a box supporting flange projecting 95 downward from the bottom along lines near the four edges thereof, a skid beneath the bottom with its ends abutting against the opposite parts of the said flange, the bottom extremities of the flange and of the skid 100 lying in the same horizontal plane, and sheet metal tongues connected with the bottom and engaging the skid for securing the skid to the bottom.

13. In a sheet metal box the combination 105 of side and end walls suitably secured together, a sheet metal bottom secured to the side and end walls and arranged with all of its parts in a single horizontal plane, a box supporting flange projecting downward 110 from the bottom along lines near the four edges thereof, and a skid secured to the sheet metal bottom with its ends abutting against the said flange at opposite points, the lower extremities of the flange and of the skid 115 lying in the same horizontal plane.

In testimony whereof I affix my signature in presence of two witnesses.

GOTTLIEB KLENK.
